DISPENSING CONTAINER

Anthony J. Parente, 2204 E. Washington Lane,
Philadelphia, Pa. 19138
Filed Sept. 14, 1965, Ser. No. 487,140
4 Claims. (Cl. 222—450)

This invention relates to a dispensing container of the type which has a pouring spout which may be opened and closed. Such containers are commonly used for containing powdered soap, salt, etc.

One object of the invention is to produce an improved dispensing container of the type set forth.

Dispensing containers, of the type set forth, generally contain materials used in measured quantities and a measuring device may not always be readily available.

It is therefore a further object to produce a container which will dispense and pour measured quantities of material.

A still further object is to provide an improved dispensing container, of the type set forth, which is reliable and inexpensive.

The full nature of the invention will be understood from the following specifications and the accompanying drawings in which:

FIG. 1 is a view partly in elevation and partly in section of a dispensing container embodying the invention when the same is not in use.

FIG. 2 is similar to FIG. 1 except that it shows the container in the process of measuring out some of its contents.

FIG. 3 is an enlarged, fragmentary, perspective view of the lower right-hand portion of FIG. 2.

FIG. 4 is similar to FIG. 3 but shows the container in the process of pouring the quantity measured as shown in FIGS. 2 and 3.

Referring to FIG. 1, dispensing container 10 includes a top wall 12, side walls 14, rear wall 16, front wall 18, and bottom wall 20. Carried by front wall 18 is spout 22, hinged at its upper edge at 24 in the usual manner, whereby the spout can be closed as shown in FIG. 1 or opened as shown in FIG. 2. It should be noted that spout 22 is at the base of the container instead of at the top, so as to pour the required amount of material into a measuring and pouring device 26 which is fully described below.

The measuring and pouring device 26 is slidably mounted in a compartment formed by extensions 28 and 30 of side walls 14 and rear walls 16 respectively, and by bottom wall 32. The pouring device includes side walls 34, bottom wall 36, rear wall 46, and front wall 38. The front portions of side walls 34 are scored as at 42 so as to be folded to the position of FIG. 3 to form measuring device 26 or to be unfolded to the position of FIG. 4 to produce an outwardly extended pouring member 52.

The upper edge of rear wall 46 is extended rearwardly normal to said wall, to form a guide member 44 which slides against the underside of bottom wall 20 of carton 10. Similarly, side walls 34 and bottom wall 36 of the measuring device are also extended rearwardly to form guide members 35 and 37 respectively, which bear against side wall extensions 28 and bottom wall 32.

Front wall 38 of measuring device 26 is provided with a handle 48 by which the measuring device may be pulled from the position of FIG. 1 to the positions of FIGS. 2 and 3. The front wall 18 of container 10 is provided with a lip 50 which is in the path of outward movement of the measuring device and which engages rear wall 46 to

2

limit the movement of said device. The position of rear wall 46 within said device is such that when lip 50 engages said rear wall as shown in FIGS. 2 and 3, the volume contained within measuring device 26 is of a predetermined amount, e.g., one cup. Graduations or similar markings may be made on the interior walls so as to provide fractional measures of the entire volume.

The operation of measuring and pouring device 26 is as follows:

Said device is moved outwardly from its compartment, by pulling handle 48 in an outward direction, until rear wall 46 engages lip 50 thereby preventing further movement of said device. When device 26 is positioned as shown in FIGS. 2 and 3, spout 22 is opened and the contents within container 10 flow out through said spout without having to tip the container. When the desired amount of material has been received in the measuring device, spout 22 is closed. Front wall 38 is pulled downward as shown in FIG. 3 to unfold the front portions of side walls 34, on either side of front wall 38, thereby forming pouring extension 52, as shown in FIG. 4, through which the contents of measuring device 26 are emptied into whatever receptacle is desired. After said contents have been poured out, front wall 38 is moved to its original position to refold side walls 34 along creases 42. The measuring device is now pushed back into its compartment whereby the operation can be performed again.

What I claim is:

1. A container having:
side walls, top, and bottom walls, and
a front wall,
a spout carried by the lower portion of said front wall,
the side and back walls of said container being ex-
tended below the bottom wall thereof to form the
side and back walls of compartment below said con-
tainer, and
a measuring and pouring device slidably mounted in
said compartment, and including:
side walls,
a bottom wall, and
a rear wall,
the front portions of the bottom and side walls of said
device being scored whereby they may be folded
to form a front wall for said measuring device and
whereby they may be unfolded to form a pouring
nozzle,
the upper edge of the rear wall of said device being
extended to form a guide member which bears
against the bottom of said container, and the side
walls of said device being extended to form lateral
guide members which slidably bear against the walls
of said compartment.
2. The structure defined in claim 1 and a bottom wall
for said compartment, and wherein the bottom wall of
said pouring device is extended to form a guide bearing
on the bottom wall of said compartment.
3. The structure recited in claim 1 and a lip depending
from the front wall of the container which is in the path
of outward movement of the measuring device to limit
the movement of said device within said compartment.
4. A container having a front wall and a bottom wall,
wall means forming a compartment below said bottom
wall,
the front end of said compartment being open,
and a material measuring and dispensing device com-
prising a rear portion formed of non-collapsible side,
bottom, and rear walls, and a front portion com-

prising scored bottom and side walls which are erectible to constitute a front wall for said device and are collapsible to constitute a pouring nozzle for said device, and
 means mounting said device for movement in said compartment to a first position in which it is wholly concealed by the bottom of the container and to a second position in which said device protrudes beyond the front wall of the container to receive material from said spout.
